UNITED STATES PATENT OFFICE.

JAMES TRIBE, OF MILWAUKEE, WISCONSIN, ASSIGNOR TO ALLIS-CHALMERS COMPANY, OF MILWAUKEE, WISCONSIN, A CORPORATION OF NEW JERSEY.

UNLOADING DEVICE.

No. 923,607.

Specification of Letters Patent.

Patented June 1, 1909.

Application filed January 22, 1906. Serial No. 297,174.

To all whom it may concern:

Be it known that I, JAMES TRIBE, a citizen of the United States, residing at Milwaukee, in the county of Milwaukee and State of Wisconsin, have invented certain new and useful Improvements in Unloading Devices, (Case B.) of which the following is a specification.

This invention relates to control mechanism and more particularly to a valve, actuating mechanism therefor, and means for holding the valve.

This invention has utility when applied to pressure control of a valve, as the inlet valve of a blower or compressor, in which relation it serves as an efficient unloading device.

Referring to the drawings: Figure 1 shows an embodiment of the control mechanism as applied to a blowing engine; Fig. 2 is a detail of the holding device.

The rockable element 1 is the inlet valve and has an arm 2 connected by a link 3 to the resilient means or spring 4, which spring 25 is connected to a fixed base plate 5. The element 1 has a second arm 6 with a pin 7 engaging slot 8 of the link 9. The link 9 is pivoted on the wrist plate 10, which wrist plate is mounted on the cylinder 11. The 30 arm 6 has a lug or block 12 thereon, which block is so positioned that the pivoted link or catch 13 mounted on the plate 5 may move into the path of the block 12 and thereby hold the element 1 against the resistance of the spring 4. The link 13 is actuated through the rod 14 connected to some fluid actuated mechanism, as for example, the Bourdon tube 15, which has communication through pipe 16 with a source of fluid pressure, stored in the receiver. The valve 1 with its arms 2 and 6 are virtually one element, and, accordingly, by this construction there is produced a device with few wearing parts.

45 Operation: When the pressure in the receiver rises above the pressure required, the tube 15 is moved or straightened sufficiently to throw the rod 14, and thereby move the link 13 into the path of block 12. The link 50 13 upon engaging the block 12, holds the inlet valve 1 open against the resistance of the continuously effective closing means 4, while the continuously operable valve opening means 9 and 10 is also rendered ineffect-

ive, the slot of the link 9 riding along the pin 7. When the receiver pressure falls to or below the required point, the Bourdon tube 15 will tend to assume a contracted form. As the link 9 in its upward pull moves sufficiently to lift the arm 6 slightly, it thereby frees the lug or stop 12 from the link 13 and permits the tube 15 to withdraw the link 13. With this link 13 withdrawn, the continuously effective means 4, having pivotal connection with the arm 3, tends to close the inlet valve 1 and thus place the blower in regular operation to deliver from the compression stroke past the delivery valve into the receiver instead of forcing the air back through the inlet valve, as in the case when link 13 holds the valve open. This link connection of the tension spring 4 with the arm 2 is such that its working angle is greatest the nearer the valve is to the end of its closing movement.

What is claimed and it is desired to secure by Letters Patent is:

1. The combination with an inlet valve, of a spring one end of which is stationary and the other end connected to said valve for moving said valve in one direction, a link provided with a slot one end of which engages the valve to positively move said valve in the opposite direction, a catch engageable with said valve to prevent its movement, and fluid actuated means to operate said catch.

2. The combination with an inlet valve of an air compressor, a spring stationarily held at one end and secured to said valve at its other end whereby it may move said valve in one direction, a link provided with a slot one end of which engages the valve to positively move said valve in the other direction, said valve being provided with a lug, a pivoted catch engageable with said lug to prevent said valve being moved by said spring or to be retained out of engagement with said lug to permit said valve to be moved by said spring, and fluid pressure actuated means secured to said catch for controlling its movement.

In testimony whereof I affix my signature in presence of two witnesses.

JAMES TRIBE.
